(57) **CLAIM**

The ornamental design for a cover glass for mounting over a solar cell, as shown and described.

DESCRIPTION

This application is related to U.S. patent Ser. No. 29/837, 819, filed May 9, 2022.

FIG. 1 is a top perspective view that illustrates the cover glass for mounting over a solar cell showing our new design;

FIG. 2 is a top plan view of FIG. 1;

FIG. 3 is a bottom plan view thereof;

FIG. 4 is a rear side elevation view thereof;

FIG. 5 is a front side elevation view thereof;

FIG. 6 is a left side elevation view thereof; and,

FIG. 7 is a right side elevation view thereof.

The broken line portion of the figure drawings is included to show portions of the article that form no part of the claimed design.
